UNITED STATES PATENT OFFICE.

JOSEPH L. CHANTEMERLE, OF BRONX, NEW YORK, ASSIGNOR, BY MESNE ASSIGNMENTS, TO SPERRY GYROSCOPE COMPANY, INC., A CORPORATION OF NEW YORK.

VISUAL SIGNAL.

Application filed August 18, 1925. Serial No. 50,894.

This invention relates to visible signal means adapted especially to be used in connection with air operated whistles on vessels without steam whistles, such as motor ships, 5 motor boats and submarines. Means have heretofore been proposed for producing a white cloud or smoke at the time the whistle cord is pulled resembling steam issuing from a steam whistle so that the pilots of other 10 ships may readily ascertain which ship in the vicinity is sounding the whistle.

One purpose of my invention is to improve upon the above type of air operated whistle, and more particularly to improve 15 upon the type of cloud or smoke producing means shown in the copending application of Chester B. Mills, Serial No. 739,787, filed September 25, 1924, assigned to the assignee of the present application.

20 Other objects of the invention are to improve upon visible signalling means in general where an anhydrous substance, such as stannic or titanium tetrachloride, is projected into the air to produce a cloud or 25 smoke.

Referring to the drawings which I now consider the preferred forms of my invention are shown.

Fig. 1 is a side elevation of one form of my 30 smoke producing means as connected up to an air operated whistle.

Fig. 2 is a side elevation of a second form of the same, partly in section.

Fig. 3 is a section through the valve controlling the smoke producing apparatus of 35 Fig. 1.

Fig. 4 is a detail view of a cap plate used in Fig. 5.

Fig. 5 is a vertical section of the smoke 40 producing apparatus of Fig. 2.

Fig. 6 is a top plan view of the same.

Fig. 7 is a vertical section of the mixing 45 chamber taken at right angles to Fig. 5.

My smoke producing apparatus may be connected up to any type of air or gas operated 50 whistle, horn or other warning signal, and is shown as connected to a whistle 1 of the diaphragm type. When so used it is operated preferably by compressed air from the whistle valve 3. A small pipe 3' leads from a point between said valve and whistle to a smoke producing apparatus. Preferably I

interpose between the whistle valve and the mixing chamber a secondary or relay valve 4. Referring first to Figs. 2 and 5, said 55 valve is shown in the form of a piston 5 mounted within the cylinder 6 and having a lower reduced portion 7 and an upper reduced portion 8. The pipe 3 from the whistle is shown as entering the valve at a port 9 below or partially below the under-surface of the piston 5, so that when air under pressure is forced into the cylinder at that point, the piston is lifted against the force of the spring 11 which surrounds the extension 8. Preferably the stem 7 has a loose fit in the cylinder head 12 so that in case the whistle valve 2 is not tight the air escaping therethrough will escape around the stem 7 without moving the valve and without entering the mixing 60 chamber. This is a distinct advantage over the prior type of whistle in which the air was led directly to the mixing chamber, since in that type any leak in the main whistle valve would cause air to escape continuously in 65 the mixing chamber and produce fumes which would quickly clog up the same. When the piston 5, moving against the action of the spring 11, passes the port 13, air escapes therethrough into the pipe 15 and from 70 thence is discharged through the jet 16 into the mixing chamber 17 and out of the top of the same at 18. The sudden admission of air into the space 10 suddenly compresses the 75 spring and forces the piston up to and past the port 13. To prevent further movement of the piston, I provide a rubber or other yielding bumper 19 on the stem 7. Said bumper is shown as held thereon by a nut 20 threaded on the end of the stem and strikes the cylinder end 12 at the upper limit of the stroke. Preferably the port 13 is so located as to reduce or eliminate the shock of the bumper 19 80 striking the said end 12. This result is accomplished by placing the port 13 so that it is uncovered before 19 strikes 12. This results in a decrease in the air pressure behind the piston, since the air then escapes through the port 13, the result being that the spring 11 slows up and practically stops the piston 85 before or by the time the bumper strikes the stop 12. As before stated, the air is led through the jet 16 into the mixing chamber 90 95 17. Said chamber is located directly above

the tank 22 containing the cloud producing liquid. Preferably but a single liquid is employed, which when the fumes therefrom are ejected into the air, produces a cloud.

Chamber 17 is shown as connected to container 22 by pipe 23. Adjacent the bottom of the container or top of the pipe is placed a thin disc 24 with a small aperture 25 therein. Said disc is shown as held in place by spring clip 26 and is for the purpose of preventing the formation of encrustations at the point where liquid enters the mixing chamber, it having been found that the liquid will drop back through the hole in the thin disc without clogging the same.

In such an apparatus it is imperative to keep it tightly closed when the smoke is not actually being produced as otherwise the air and fumes from the Diesel engines of the ship quickly combine with the vapors in the chamber to form a thick deposit. For this purpose I have shown a cap or closure 55 which normally fits tightly on top of the opening 18 and may be provided with a rubber block 56 to seal the opening. Preferably I provide automatic means for opening said closure when the whistle is blown or when the signal is given. For this purpose I have shown the cap as provided with a laterally extending arm 27 secured to the reduced portion 28 of stem 8 as by nut 30. Said extension may also be provided with a downwardly extending skirt 29 to prevent foreign matter from entering the top of cylinder 6, enclosing spring 11. Adjacent the top of said extension 8 are also provided spiral flutes 31 which engage a squared opening 32 in the cover plate 33 of cylinder 6. By this construction it will readily be apparent as the piston 5 is raised by the air pressure, the cap 56 will be simultaneously lifted and also rotated without the path of emerging smoke (see Fig. 2 and also dotted line position in Fig. 5).

The entire device may be clamped to the ship's funnel as by means of brackets 35-36. Preferably I provide a shield 37 for enclosing the container 22 for the liquid. This is for the purpose of preventing too great variations in temperature in the liquid due to the sun's rays and heat from the stack, since high temperatures cause undue expansion of the liquid and also fuming. Also preferably I only partially fill the container 22 as indicated by dotted line 22' to allow sufficient air space for expansion and contraction of the liquid.

In Figs. 1 and 3 is shown a form of the apparatus especially adapted for submarines. In this instance the cap 55' is hinged at 39 to bracket 40 on the side of the chamber 17'. Said hinge may be provided with an eccentric 41 to equalize the pressure of the cap on the top of 18' of the closure. On its opposite side, said cap is pivoted to a link 42' which

is hinged to an extension 28' of piston valve 5'. The valve mechanism in this instance is especially designed to prevent the possibility of any water getting into the system when the submarine is submerged. For this purpose the piston 5' does not itself open the valve or port 13' leading to the smoke producing apparatus but actuates an intermediate mechanism for doing so, and said valve is located so that any water leaking past the piston will not enter the valve but will collect at the bottom of housing 58 where it may be drawn off by petcock 59. As shown in Fig. 3 the piston 5' is provided with a downwardly extending stem 45 having a shoulder 46 thereon and also being provided adjacent its lower end with an enlarged and preferably hollow cylindrical portion 47 having a collar 48 at the base thereof. A compression spring 11' bears at one end on said collar 48 and at the other end against the lower end 49 of the cylinder 6', thereby tending to hold the piston 5' in its lowermost position. Pivoted at 50 in housing 58 is an arm or lever 51. At its inner end said arm is provided with a fork 52 taking a round stem 45 and adapted to be engaged by the shoulder 46 when the piston 5' is raised. At its opposite end said arm 51 engages the top of a valve 53 which normally closes a port 13' leading into the opening 54 connected to pipe 15' which leads to the smoke mixing chamber 17'. Said valve is shown as normally closed by spring 55 but is opened when struck by arm 51. When the whistle valve is opened, therefore, air enters the housing 58 and cylinder 6' through the pipe 3' raising piston 5' upwardly against the spring until the shoulder 46 strikes the fork 52 thereby rotating the arm 51 and opening valve 53. This permits the air to flow through channel 56 and port 13' to the mixing chamber 17'.

In this form of the apparatus also I provide an extra tank 60 connected to the liquid container 22' by pipe 61. Said tank is for the purpose of allowing free expansion of the liquid in the container 22' so that the liquid will not push up through the pipe 23 and into the mixing chamber owing to the temperature variations.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I

claim and desire to secure by Letters Patent is:

1. A smoke signal comprising a container for the fluid which when the vapor thereof is entrained in air produces smoke, a mixing chamber connected thereto, an air jet therein for entraining the said vapor, a source of compressed air, a primary valve for controlling said source to operate said signal, and an 10 automatically-operated secondary valve between said primary valve and said jet.

2. A smoke signal comprising a container for the fluid which when the vapor thereof is entrained in air produces smoke, a mixing 15 chamber connected thereto, an air jet therein for entraining the vapor, a source of air under pressure connected to the said jet, a primary valve for controlling said source to operate said signal, and a pressure-operated secondary valve between said primary valve and 20 said jet.

3. A smoke signal comprising a container for the fluid which when the vapor thereof is entrained in air produces smoke, a mixing 25 chamber connected thereto, an air jet therein for entraining the vapor, a source of air under pressure connected to the said jet, means for controlling said source to actuate said signal, a closure for said chamber, means for 30 normally maintaining the same closed, and a piston for opening said closure on actuation of the signal.

4. A smoke signal comprising a container for the fluid which when the vapor thereof is entrained in air produces smoke, a mixing 35 chamber connected thereto, an air jet therein for entraining the vapor, a source of air under pressure connected to the said jet, a primary valve for controlling said source to operate said signal, a closure for said chamber, means for normally maintaining the same closed, and pressure-operated means 40 between said valve and jet for opening said closure on actuation of the valve.

45 5. A smoke signal comprising a container for the fluid which when the vapor thereof is entrained in air produces smoke, a mixing chamber connected thereto, an air jet therein for entraining the vapor, a source of air 50 under pressure connected to the said jet, means for controlling said source to actuate said signal, a closure for said chamber, means for normally maintaining the same closed, and a piston for opening said closure and 55 moving it outside the path of the issuing smoke upon actuation of the signal.

60 6. A smoke signal comprising a container for the smoke producing substance, a mixing chamber above said container and connected thereto, an air jet therein for entraining the vapor from said substance, a source of air under pressure connected to the said jet, a valve for controlling said source, a disc having an aperture therein located in the connection between said container and jet for 65

the purpose specified, and a split ring for holding said disc in place.

7. A visual signal including a whistle, a whistle valve, means for leading off a portion of the air used in operating the same, 70 a visible signalling means operated by said air, and a relay valve between said whistle valve and means, said relay valve having a slow leak for the purpose specified.

8. A smoke signal comprising a smoke 75 producing fluid, a mixing chamber, an air jet therein for entraining the vapor from said fluid, a source of air under pressure, means including a control valve for connecting said source to said jet, a primary 80 valve for operating said signal, and a pressure-operated secondary valve between said primary valve and said jet, said secondary valve having a slow leak for the purpose specified. 85

9. In a visual signal, a relay valve for controlling the production of the visible signal, said valve comprising a cylinder, a piston therein, a stop to limit the piston movement, a spring for normally holding said piston in 90 one position, an inlet port to one side of the piston, and an outlet port normally closed by said piston, the latter port being so positioned as to be uncovered by said piston in time to reduce the piston speed before it 95 strikes the stop.

10. A smoke signal comprising a smoke producing fluid, a mixing chamber, a closure therefor, an air jet therein for entraining the vapor from said fluid, a source of air under 100 pressure means connecting said source to said jet, a primary valve in said last-named means for operating said signal, and an automatically-operated secondary valve between said primary valve and said jet, said 105 secondary valve also serving to open said closure.

11. A smoke signal comprising the combination with the source of compressed air, of a smoke producing fluid, a mixing chamber, an air jet therein for entraining the vapor of said smoke-producing fluid, a source of air under pressure, means including a controlling valve for connecting said source to said jet, a closure for said chamber, means for normally maintaining the same closed, a piston connected to said closure governed by said air under pressure, and a connection between said piston and closure to open the latter on actuation of the 115 former. 120

12. A smoke signal comprising the combination with the source of compressed air, of a smoke-producing fluid, a mixing chamber, an air jet therein for entraining the vapor of said smoke-producing fluid, a closure for said chamber, means for normally maintaining the same closed, a piston connected to said closure governed by said air 125 under pressure, and a connection between 130

said piston and closure to open the latter and rotate it without the path of the smoke on actuation of the former.

13. In a visual signal for motor ships, the combination with a substance which fumes when exposed to air, of a container for said substance, both of which are adapted to be

mounted in the exposed position on the ship, and a heat shield around said container for the purpose specified.

10 In testimony whereof I have affixed my signature.

JOSEPH L. CHANTEMERLE.
